LIQUID EVACUATING SYSTEM

Russell W. Sinks, Dayton, Ohio

Application June 18, 1935, Serial No. 27,263

3 Claims. (Cl. 225—20)

This invention relates to an evacuating system that permits liquid to flow efficiently by gravity from a container through a valve that admits displacing air simultaneously with the discharge of the liquid.

One of the features of the present invention is the arrangement of tubes communicating with the liquid outlet and air inlet which are interconnected by branch tubes whereby a hermetic seal is maintained in the tank until the liquid level is very low.

The system finds particular use in dispensing containers wherein volatile liquids are stored which may create an increased pressure within the container. Another advantage of the present invention is that the construction lends itself to dispensing beer inasmuch as the gases and vapors are retained in the container and therefore no matter how often beer is drawn, that portion remaining in the container will not become flat.

Further objects of the invention are to provide a dispensing tank of the character referred to that is strong, compact and durable, thoroughly reliable for its intended purpose, very simple in construction and operation and that is comparatively inexpensive to manufacture.

With the foregoing and other objects in view the invention consists of a novel construction, combination and arrangement of parts as will be hereinafter more specifically described and illustrated in the accompanying drawings wherein is disclosed an embodiment of the invention, but it is to be understood that changes, variations and modifications may be resorted to without departing from the spirit of the claims hereunto appended.

In the drawings wherein like reference characters denote corresponding parts throughout the several views:

Figure 1 is a top plan view of a dispensing tank embodying an evacuating system constructed in accordance with the present invention.

Figure 2 is a fragmentary side elevation thereof. Figure 3 is an enlarged fragmentary front elevation thereof.

Figure 4 is a vertical section taken substantially on lines 4—4 of Figure 3.

Figure 5 is a front elevation of the base member of the valve housing.

Figure 6 is a face view of one of the gaskets.

Figure 7 is a face view of the valve plate.

Referring to the drawings in detail, A indicates generally a container or tank of any desired shape and for the purpose of illustration there

is shown a tank of cylindrical configuration having a circular side wall 7 and end walls 8, 9 joined to the ends of the side wall. A threaded filling opening 10 may be located at various points and for convenience I have shown this opening at the top of the side wall to one side of the tubes so as not to interfere with the tubes, and this opening is closed to make an air tight fit by the cap 11. It will be understood that in the assembled relation the tank is air tight.

Adjacent the lower margin of front end wall 8 are a pair of circular openings 12, 13 through which extend outer portions of the air displacing tube 14 and the liquid outlet tube 15 as will be understood by referring to Figure 4 of the drawings. These openings are in diametric alignment with each other and the tubes are rigid. Liquid outlet tube 15 is straight and is placed as nearly parallel to the bottom of the tank as possible and terminates in an open inner end adjacent the inner wall 9. The inner end of tube 15 terminates as close to inner wall 9 as possible, but the space between the wall and end of the tube should be sufficient to insure no capillary restriction of the liquid between the wall and the end of the tube. A safe distance between the end of the tube and the wall 9 has been found to be from one-third to the full diameter of the tube 15. Air displacing tube 14 may be of compound curvature as shown, or it may be straight, but it is diverging from tube 15 from the front wall 8 to the back wall 9. The inner end of tube 14 terminates at a point spaced from the end wall 9 substantially the same distance as the tube 15. Tube 14 also terminates as close to the top wall of the tank as possible. Both tubes lie substantially in the same plane and the branches to be hereafter described, lie in the plane with the tubes. The compound curvature of tube 14 should be such that the curves in the tube will not permit the trapping of air entering the tank to replace the liquid being drawn therefrom.

There is a branch tube 16 inclining rearwardly at an angle and the ends of this tube join and communicate with tubes 14 and 15. Tube 16 is straight and is positioned in the tubes 14 and 15 at a point from front end wall 8 at least twice the length of the branch tube 16. The incline of this branch tube 16 should be at such an angle that will most readily relieve the pressure in the tube 14. Another branch tube 17 is curved rearwardly and joins and communicates with air displacement tube 14 at one end and the liquid outlet tube 15 at the other end. Branch tube 17 joins tube 15 adjacent the inner end thereof and

tube 14 at a point outwardly of a perpendicular to its juncture with the tube 15. By extending the two branches between liquid outlet tube and air displacement tube at the points indicated, 5 this arrangement reduces the liquid pressure in tube 14 while liquid is being withdrawn from the container, thereby reducing the air resistance in the air displacement tube.

The valve housing is indicated generally at B 10 and consists of a circular base member 18 and a circular cap member 19. The base member has a flat inner face secured to the lower portion of front wall 8 of the tank. Base member 18 and cap member 19 are formed with peripheral flanges 15 20, 21 respectively which when assembled have the edges in abutting relation. The abutting edges of the flanges form an internal, circular valve chamber 22 between the confronting faces of the base and cap member. The inner end of 20 spindle bolt 23 is anchored in the center of the base member 18 and extends outwardly from the aperture in the cap member and has a nut 24 on the free end that holds the valve housing in assembled relation.

25 There are a pair of circular openings 25, 26 in the cap member in diametric alignment with each other and the upper opening 25 is counter bored as at 27 to receive the end of the air displacing tube 14. Lower opening 26 is counter bored as at 28 to receive the outer end of liquid outlet tube 15. It will be seen that these openings 25, 26 are in communication with the interior of the tank through the respective tubes that are in registry therewith. Cap member 19 30 is formed with a circular opening 29 which is in alignment with opening 25 and through this opening 29 air passes into the liquid displacement tube 14. There is a spout 30 on the cap 19 having the passage 31 therein and this passage is in alignment with opening 26 in the base member.

40 For about a quadrant of the circumference the confronting edges of the flanges 20, 21 are cut away to provide a slot 32 in the periphery of the valve housing B and this slot communicates with 45 the valve chamber 22. One of these cutaway portions is indicated at 32 on the flange of the base member shown in Figure 5 of the drawings. A flat disk valve plate 33 is rotatably mounted in the valve chamber 22 on an intermediate portion 50 of the spindle bolt 23 which passes through a central opening 34. The edges of the valve plate 33 bear snugly against the outer walls of the valve chamber to make an air tight fit. Extending through the valve plate 33 are a pair of valve 55 ports 35, 36 which ports are in diametric alignment with each other. From the periphery of the valve plate 33 is an outwardly projecting extension 37 which is disposed at right angles to the diameter passing through the valve ports and this 60 extension projects through the slot 32 so that the ports may be brought into registry with and closed with respect to the aligned openings in the cap member and base member. On the outer end of extension 37 is a handle 38.

65 To make an air tight fit between the confronting faces of the valve plate 33 and the walls of the chamber 22 there are a pair of gaskets mounted one to each side of the valve plate and one of these gaskets is shown in Figure 6 of the 70 drawings and indicated at 39. In the center of the gasket is an opening 40 through which extends spindle bolt 23 whereby the disk is securely held in position. Each of the disks are formed with diametrically aligned openings 41, 42. The 75 upper opening 41 registers with the aligned open-

ings 25 in the base member and 29 in the cap member while the lower opening 42 registers with the inner end of passage 31 and the opening 26 in the base member. It will thus be seen that when the extension 37 is in a vertical position as 5 shown in Figures 1 and 3 of the drawings no air will be passing through tube 14, nor will there be any liquid discharged from the spout. By turning the extension approximately forty-five degrees, the ports 35 and 36 in the valve plate 10 will register with the aligned openings in the cap and base member whereby air will be admitted to the air displacement tube 14 and liquid discharged from the spout 30. It will therefore be obvious that air is simultaneously admitted to 15 the interior of the tank A when the liquid is discharged from the spout 31 thereby allowing air to displace liquid being withdrawn from the tank.

The advantages to be gained by using the liquid evacuating system and valve are that when the 20 container is completely filled with liquid, a perfect hermetic seal is obtained in all positions. When the container is reposing on the side wall 7, the hermetic seal is maintained until the liquid level falls below the point where branch 16 joins the 25 tube 14. When resting on the rear wall 9, the hermetic seal is maintained until the liquid level falls below the inner terminals of the tubes 14 and 15. When the container is resting on the 30 front wall 8, the hermetic seal is maintained until the liquid level falls below the point where branch 16 joins the tube 14. When the container is resting on side wall 7 with the tube 15 at the bottom, the liquid will at all times evacuate freely through the open valve until the liquid level is below the 35 tube 15.

Having thus described the invention, what is claimed as new is:

1. The combination with a tank formed with a pair of openings in spaced relation to one another, one for a liquid outlet and the other for an air inlet to displace the liquid, a liquid discharge tube disposed in the tank and communicating with the outlet opening, an air displacement tube disposed in the tank and communicating with the air inlet opening, said tubes diverging from each other from a point where they communicate with the openings, said tubes joined by plural branches between the free terminals and the points where they communicate with the openings, and a valve for controlling said openings.

2. The combination with a tank formed with a pair of openings in spaced relation to one another, one for a liquid outlet and the other for an air inlet to displace the liquid, a straight discharge tube disposed in the tank in the plane of the outlet opening and communicating with the outlet opening, an air displacement tube disposed in the tank and communicating with the air inlet opening, said air displacement tube diverging from the liquid discharge tube from a point where the tubes communicate with the openings, said tubes joined by plural branches between the free terminals and the points where they communicate with the openings, and a valve for simultaneously controlling said openings.

3. A valve comprising a housing formed with a base and cap member adapted to be assembled in face to face relation, said base member adapted to be carried by a tank formed with a pair of openings to be controlled by the valve, said base and cap member formed with peripheral flanges having their free edges in abutment to provide a continuous internal valve chamber coextensive 75

with the remaining portion of the confronting faces of said members, portions of the flanges cut away to provide a slot communicating with the valve chamber, said base and cap member formed with aligned openings in alignment with the first mentioned openings in the tank, a valve plate rotatably seated in the valve chamber formed with a pair of valve ports and an ex-

tension arm projecting through said slot, and a pair of apertured gaskets disposed one to each side of the valve plate to make a tight fit between the valve plate and the walls of the valve chamber, and means for securing the cap, gaskets and valve plate together to make an air tight valve. 5
